UNITED STATES PATENT OFFICE

168,978

STOCKING

Isadore Stillman, Philadelphia, Pa.

Application March 18, 1952, Serial No. 18,953

Term of patent 14 years

(Cl. D47—7)

To all whom it may concern:

Be it known that I, Isadore Stillman, a citizen of the United States, residing at Philadelphia, Pennsylvania, have invented a new, original, and ornamental Design for a Stocking, of which the following is a specification, reference being had to the accompanying drawing, forming a part thereof.

Fig. 1 is a side view of a stocking showing my new design.

Fig. 2 is a fragmentary rear elevational view thereof.

I claim:
The ornamental design for a stocking, substantially as shown.

ISADORE STILLMAN.
